UNITED STATES PATENT OFFICE.

CLARENCE B. HODGES, OF DETROIT, MICHIGAN.

LOW-WATER ALARM.

SPECIFICATION forming part of Letters Patent No. 678,735, dated July 16, 1901.

Application filed September 19, 1900. Serial No. 30,473. (No model.)

To all whom it may concern:

Be it known that I, CLARENCE B. HODGES, a citizen of the United States, residing at Detroit, county of Wayne, State of Michigan, have invented a certain new and useful Improvement in Low-Water Alarms; and I declare the following to be a full, clear, and exact description of the invention, such as will enable others skilled in the art to which it pertains to make and use the same, reference being had to the accompanying drawings, which form a part of this specification.

This invention relates to low-water alarms, and has for its object improvements in that class of alarms in which a signal is sounded by the automatic opening of a valve and admission of steam to the signal whenever the water in the boiler reaches a predetermined depth.

20 In the drawings, Figure 1 shows the alarm in elevation, parts being sectioned. Fig. 2 is a detail of an air-outlet valve at the top of the structure.

A indicates a stand-pipe screwed into a coupling B, of which the lower end is screwed into an elbow C. The elbow C is adapted to be and is intended to be screwed into the lower gage-cock fitting of a steam-boiler. The top of the stand-pipe A is closed in by a cap, 25 a, through which there is an air-passage b, stopped by a needle-valve c. The valve c has a passage d through its stem, and an opening e leads into this passage. The valve c when screwed in closes the passage d, and when 30 screwed out, so that the passage b is open, there is a free passage for air from inside the stand-pipe to the outer air.

On the top of the cap a are two bearings ff, in which is hung a lever D. The lever D has 35 a short arm g and a long arm h. The short arm is connected by a link-bolt g' to a spur b' on the coupling B. The connection of the bolt g' to the spur b is by means of a screw and nuts n n, by means of which the effective 40 length of the link-bolt may be adjusted. The long arm h of the lever D is connected by a link-support h' to a bell-crank lever k, that is fulcrumed to a spur K, that extends from the bottom of a whistle-standard s. At the 45 top of the whistle-standard s is supported a steam-whistle T, and below the steam-whistle T is a valve arranged to be held in a normally-

closed position by a spring t, that surrounds its projecting stem. The projecting stem of the valve engages an arm of the bell-crank lever k, and the valve is opened by the pressure of the arm k against the stem. 55

The whistle-standard and the pipe leading into it are secured to a bracket R of the coupling B, and a steam-pipe p leads into it from 60 the steam-space in the boiler. Preferably it is arranged to be connected to the upper gage-cock.

Inside the stand-pipe is a loose vertical rod, (shown in the drawings as a hollow rod r,) 65 though either a hollow or solid rod may be used. The rod serves to break what may be termed the "seal" that arises because of the long column of water supported in the long narrow stand-pipe A. 70

The operations of the device are as follows: The elbow C leads from the boiler at a lower point than the steam-pipe p, and when the water in the boiler is lower than the opening in the steam-pipe p there is free access of 75 steam through the pipe p as far as the valve at the top of the whistle-standard, because of the steam-pressure in the boiler and because of the comparative coolness of the long and exposed standard A, said standard A 80 being full of water. As soon, however, as the water falls to a level with the entrance of the elbow C the water in the stand-pipe begins to run out, and the rod r causes it to run out rapidly, and the stand-pipe A fills with 85 steam instead of water. The water in the stand-pipe A was comparatively cool, much cooler than the water in the boiler, because of its much greater exposure to radiation and because it was not circulating, but stagnant, 90 and consequently the stand-pipe A increases in temperature rapidly as soon as the water runs out and the steam takes its place.

The increase of temperature increases the length of the stand-pipe, and its length increases more rapidly than does the length of the link g' or of the link h', and the lever D is turned on its fulcrum. The link h' pulls the bell-crank lever k, pushes in the valve-stem, and opens the valve to the whistle, 95 and the whistle at once signals the condition of the water.

I have found experimentally that this alarm requires about two minutes' time before the

signal is sounded if the rod r is omitted and that it will give the signal within thirty seconds' time after the steam begins to find entrance to the elbow C if the rod r is included.

5 What I claim is—

In a low-water alarm, in combination with a vertically-disposed stand-pipe, connections adapted to admit steam to the interior of the stand-pipe, a whistle, couplings connecting the whistle to the pipe near the bottom thereof, a valve controlling the passage of steam through the couplings, a lever arranged to

actuate the valve, a link joining the lever and the top of the stand-pipe, and a loose rod located in the stand-pipe and adapted to break 15 the seal of the water-column therein, substantially as described.

In testimony whereof I sign this specification in the presence of two witnesses.

CLARENCE B. HODGES.
